UNITED STATES PATENT OFFICE

WILLIAM D. PENNINGTON AND JOHN R. PENNINGTON, OF CHICAGO, ILLINOIS; OLIVE B. PENNINGTON, ADMINISTRATRIX OF SAID JOHN R. PENNINGTON, DECEASED, AS-SIGNOR, BY MESNE ASSIGNMENTS, TO SAID WILLIAM D. PENNINGTON

CLOCK-BANK DEVICE

Application filed June 27, 1925. Serial No. 39,881.

Our invention relates to clock bank devices.

One of the objects of the invention is to provide a simple, practical and effective clock bank device.

5 Another object of the invention is to provide a clock bank device in which the use of a coin is necessary in order to wind the clock, and furthermore, one in which the coin must be deposited after being used in order to ensure the running of the clock.

10 Other objects will appear and be pointed out hereinafter.

In the accompanying drawings Fig. 1 is a rear view of the clock bank device embodying 15 our present invention;

Fig. 2 is a similar view with an outer plate removed;

Fig. 3 is a view similar to Fig. 2 but with the inner plate removed;

20 Fig. 4 is a view similar to Fig. 3 with the operating mechanism in a different position.

Referring to the drawings, we show a clock bank having a base 1 and a casing 2 mounted thereon.

25 In Fig. 1 is shown a winding thumb piece 3 which may be turned by hand in order to wind the clock. A coin opening 4 is formed in the outer rear plate 5.

Referring to Figs. 3 and 4, a removable 30 coin holding device 6 is provided with three apertures or recesses 7, 8 and 9, to receive the coin, said apertures or recesses being of different size to accommodate different denominations of coins. A coin deposited in the

35 opening 4 will come into position in one of the apertures 7, 8 or 9 of the movable coin holder 6. The latter is preferably in the form of a rotary plate mounted for rotation on a shaft or spindle 10 and provided with teeth 11 adapted to engage a spring 12 to hold the member 6 against backward rotation. A thumb piece 13 is mounted on shaft 10 so as to permit the rotary movement of member 6, to bring the right aperture in position for the

40 coin and also allow the coin to be moved upwardly to operate on the mechanism as will be explained.

A swinging arm 14 is mounted on a pivot 45 15 and provided with a projection or abutment 16 in the path of a coin 17 carried by the

rotary member 6, the coin 17 acting to strike abutment 16 and thereby swing arm 14 when said member 6 is rotated by thumb piece 13 so as to move coin upwardly from position of Fig. 3 to position of Fig. 4. A spring 19 is 55 connected with member 14 and also with the side of the clock at 20, said spring 19 tending to hold or move member 14 in or toward its retracted or normal position, as shown in Fig. 3, and in which it is against or substantially 60 against the winding stem 28.

When the coin 17 strikes abutment 16 and swings member 14 outwardly or to left hand position, as shown in Fig. 4, said member 14 also swings a supplemental pivoted member 65 24 in the same direction, because of engagement of member 14 with a projection or flange 25 on said member 24. The latter is provided with a tooth or prong 26 adapted to engage a recess 27 in winding stem 28 and 70 normally this tooth 26 because of engagement with recess 27 as shown in Fig. 3, will prevent the clock from being wound. The use of the coin, however, will unlock the winding stem 28 and so permit the clock to be wound, because when coin 17 strikes abutment 16 and swings member 14 outwardly and thereby causes member 24 to swing outwardly tooth 75 26 becomes disengaged from recess 27 and thereby permits winding stem 28 to be turned so in a contra-clockwise direction so as to wind the clock.

In order that the coin 17, or in other words in order that a single coin may not be used to allow winding of the clock repeatedly, or in 85 other words, to ensure the use of successive coins to secure successive windings of the clock and thereby ensure saving, arrangement is made by which the clock may be held against running until the coin which has been 90 used to permit winding, has been deposited beyond recovery.

In the arrangement shown as second supplemental pivoted device 30 is shown pivotally mounted at 31 on arm or end portion 32 95 of swinging member 14, and this pivoted member 30 is provided with a hook or tooth 33 adapted to engage a recess 34 in winding stem 28, the engagement being such as to permit winding of the clock but to prevent turn- 100

ing of the winding stem in a clockwise direction which has to be done in order that the clock may run. In other words the member 32 with its hook or tooth 33 may lock the clock against running or release it so that it may run. In Fig. 3 the clock is shown released so that it may run. In Fig. 4 it is shown locked so that it may not run. In Fig. 4, however, the stem 28 is shown released by the coil mechanism so that the clock 10 may be wound to prevent the use of the single coin 17 and holding of the same in the position of Fig. 4, so that the clock may be repeatedly wound. Member 30 is held by spring 37 so that its tooth or prong 33 engages recess 34, and so as long as the parts are in the condition of Fig. 4 the clock may not run. Therefore to permit the clock to run the coin 17 must be moved by member 15 20 25 30 35 40 45 50 55 60 65 70 75 80 85 90 95 100 105 110 115 120 125 130 135 140 145 150 155 160 165 170 175 180 185 190 clock to prevent running of the clock, said third swinging member being adapted to be spring actuated to engage the winding stem to prevent running of the clock when the 5 first swinging member is actuated by a coin and being provided with means whereby it will be engaged and actuated by the first swinging member to withdraw and disengage its tooth or prong from the winding 10 stem and thereby allow the clock to run when the first swinging member is released and allowed to return to normal position by the movement of the coin beyond the abutment of the first swinging member and means for 15 ejecting the coin from the coin carrier and depositing the same.

In witness whereof, we hereunto subscribe our names this 25th day of June, A. D., 1925.

WILLIAM D. PENNINGTON.

20 JOHN R. PENNINGTON.
